UNITED STATES PATENT OFFICE.

DAVID M. WATKINS, OF PROVIDENCE, RHODE ISLAND.

SAFETY DEVICE.

No. 851,909.

Specification of Letters Patent.

Patented April 30, 1907.

Application filed March 17, 1906. Serial No. 306,590.

To all whom it may concern:

Be it known that I, DAVID M. WATKINS, of Providence, in the county of Providence and State of Rhode Island, have invented certain new and useful Improvements in Safety Devices; and I do hereby declare the following specification, taken in connection with the accompanying drawings, forming a part of the same, to be a full, clear, and exact description thereof.

My invention relates to a safety device for use in jewelers' presses and is especially designed for use in that class of presses known as a drop press in which one part of the die is carried in a weight which is raised by a strap or similar device, and then released so as to drop by gravity upon the object below, which rests upon the other part of the die secured to the bed of the machine. In machines of this character which are operated by power, the weight or drop frequently gives a double blow, the second blow being accidental or unintentional, and if this occurs while the operator is withdrawing the object which has been operated upon or is placing a new object on the die, his hands or fingers are liable to be struck by the drop and severely injured. The straps which raise the drops also frequently break without warning and allow the drop to fall and produce injury to the operator.

The object of my invention is to provide a safety device for use on machines of this character, which will be operated by the drop every time it falls, to remove the hands of the operator out of the path of the drop and away from all danger of injury thereby.

To this end my invention consists in the novel construction and combination of parts hereinafter described and claimed, reference being had to the accompanying drawings, in which

Figure 1 is a front perspective view of a portion of a drop press embodying my improved safety device; Fig. 2 is a horizontal sectional view on the line $x-x$, Fig. 1; Fig. 3 is a side elevation of a portion of the safety device.

Referring to the drawings, 1 represents the bed of the machine which is mounted upon suitable standards 2 and upon which is securely mounted the stationary die 3. The standards 2 are provided with the uprights 4 having the ways 5 on their inner faces for the drop 6 to slide upon. Mounted in the bottom of the drop 6 is the movable die 7 and se-

cured to the top of the drop is an operating strap 8, all of which construction is old and well-known.

Secured to one of the uprights 4 is a bracket 9, in which is loosely mounted one end of a rock-shaft 10, the other end of said rock-shaft being mounted in the bed 1. Secured to the rock-shaft 10 is a plate or arm 11 which is arranged to swing across the stationary die 3 in close proximity thereto. The free end portion 12 of the arm 11 is narrower than the fixed end portion 13, the lower edge of which extends below the top surface of the die 3, and said portion 12 is arranged at an angle to the portion 13, as shown in Fig. 2, for a purpose to be hereinafter described.

Secured to the rock-shaft 10 is a cam-bar 14 constructed with a cam surface 15 which is located in the path of the drop 6 and connected at its lower end to the arm 11. The upper end 16 of the cam-bar 14 is bent at an angle and arranged to engage the outside of the upright 4 to limit the movement of the rock-shaft in one direction and the lower end 75 of the cam surface 15 is adapted and arranged to engage the inside of said upright 4 to limit the movement of said rock-shaft in the other direction.

The operation of the device is as follows: 85 When the drop is in inoperative or raised position the arm 11 is held by a torsional spring 17 interposed between the bracket 9 and the cam-bar 14 in back of the stationary die 3, as shown in full lines in Fig. 2. This position of the arm 11 allows the operator free access to the die 3, to change or adjust the same or to place the work to be operated upon thereon. With the arm 11 in this position the cam surface 15 occupies a position directly beneath the drop 6 and in the path thereof. With the parts in this position, when the drop 6 falls either in the regular operation of the press or by accident, the lower outside edge of said drop engages the upper end of the cam surface 15 and as it slides along said cam surface it rocks the shaft 10 and swings the arm 11 forward and across the die 3 into the position shown in dotted lines in Fig. 2. It will be obvious that as the arm 11 swings forward across the die 3, said arm will remove the hands or hand of the operator from beneath the drop 6 should they happen to be in such position.

The fixed end portion 13 of the arm 11 is arranged at an angle to the free end portion 12 so as to strike the hand of the operator a

glancing blow instead of a direct blow, and the hand is swept out from under the drop in a manner not liable to injure the hand. As the stock or work upon which the drop 6 operates varies in thickness and becomes more or less buckled when struck by said drop, it is necessary to provide more or less space between the lower edge of the free end portion 12 of the arm 11 and the face of the die. In order to prevent the fingers of the operator from being caught in this space between the arm 11 and the face of the die 3, the fixed end portion 13 of the arm 11 is constructed to extend below the face or top of the die 3 and so as to strike the hand in advance of the end portion 12 and sweep the fingers off of the die and from under the drop.

I do not wish to limit myself to the exact construction shown and described, as changes may be made in the details of construction without departing from the spirit and scope of the invention.

What I claim as my invention and desire to secure by Letters Patent is:

1. In a press or similar device, the combination, with a work-support, of an arm adapted to reciprocate across said work-support, said arm being provided with a projection extending below the top of said work-support, substantially as described.

2. In a press or similar device, the combi-

nation with a work-support, of an arm adapted to reciprocate across said work-support, the fixed end of said arm being at an angle with the plane of movement of the arm and provided with a projection extending below the top of the work-support, substantially as described.

3. In a press or similar device, the combination of a stationary die, a die mounted in a movable carrier, a rock-shaft provided with a cam extending into the path of the movable carrier and adapted to be operated thereby, an arm secured to said rock-shaft and adapted to swing across the stationary die, and means for limiting the movement of the rock-shaft, substantially as described.

4. In a press or similar device, the combination, with a suitable frame, of a stationary die, a die mounted in a movable carrier, a rock-shaft mounted on the frame, a cam-bar secured to said rock-shaft and extending into the path of the movable carrier, said cam-bar being provided with means for limiting the movement of said rock-shaft, and an arm secured to said rock-shaft and adapted to swing across the face of the stationary die, substantially as described.

DAVID M. WATKINS.
